[57] CLAIM

The ornamental design for a corner lamp, as shown and described.

DESCRIPTION

FIG. 1 is a perspective view of a corner lamp showing my new design;

FIG. 2 is a front elevational view thereof;

FIG. 3 is a top plan view thereof;

FIG. 4 is a side elevational view thereof as seen from the right side of FIG. 2, the opposite side being substantially the same in appearance;

FIG. 5 is a rear elevational view thereof; and

FIG. 6 is a bottom plan view thereof.

Fig. 3.
